Primary Examiner — Jeffrey D Asch*Assistant Examiner* — Rebekah A Caruso(74) *Attorney, Agent, or Firm* — Pitts & Lake, P.C.(57) **CLAIM**

I claim the ornamental design for a sound reflector, as shown and described.

DESCRIPTION

FIG. 1 is a perspective view of a design of the present invention for a sound reflector;

FIG. 2 is a front view of the sound reflector of FIG. 1;

FIG. 3 is a rear view of the sound reflector of FIG. 1;

FIG. 4 is a right-side elevation view of the sound reflector of FIG. 1, the opposite left-side elevation view being a mirror-image of this figure; and,

FIG. 5 is a top view of the sound reflector of FIG. 1, the opposite bottom view being an inverted image of this figure. In FIG. 1, features of a stand for the sound reflector are shown in broken lines. These features are for illustrative purposes only and form no part of the claimed design.
